UNITED STATES PATENT OFFICE.

ANGIE L. HANSEN, OF CHICAGO, ILLINOIS.

DESIGN FOR AN ACETYLENE-LAMP.

42,917.

Specification for Design.

Patented Aug. 20, 1912.

Application filed January 18, 1912. Serial No. 672,000. Term of patent 14 years.

To all whom it may concern:

Be it known that I, ANGIE L. HANSEN, a citizen of the United States, residing at Chicago, in the county of Cook and State of Illinois, have invented a new, original, and ornamental Design for Acetylene-Lamps, of which the following is a specification, reference being had to the accompanying drawing, forming part thereof.

The figure is a plan view of an acetylene lamp, showing my new design.

I claim:

The ornamental design for an acetylene lamp, as shown.

ANGIE L. HANSEN.
